FOREIGN PATENT DOCUMENTS

GB 2078508 A 1/1992

Primary Examiner—Philip S. Hyder
(74) Attorney, Agent, or Firm—Synnestvedt & Lechner LLP(57) **CLAIM**

I claim the ornamental design for an exercise and stretching pole, as shown and described.

DESCRIPTION

FIG. 1 is a side view of an exercise and stretching pole in accordance with my new design;

FIG. 2 is top view of the exercise and stretching pole of FIG. 1;

FIG. 3 is a bottom view of the exercise and stretching pole of FIG. 1;

FIG. 4 is a side view of an exercise and stretching pole in accordance with an alternative embodiment of my new design;

FIG. 5 is top view of the exercise and stretching pole of FIG. 4;

FIG. 6 is a bottom view of the exercise and stretching pole of FIG. 4;

FIG. 7 is a side view of an exercise and stretching pole in accordance with an alternative embodiment of my new design;

FIG. 8 is top view of the exercise and stretching pole of FIG. 7; and,

FIG. 9 is a bottom view of the exercise and stretching pole of FIG. 7.

The broken line portions of the disclosure are for illustrative purposes only and form no part of the claimed design.
